UNITED STATES PATENT OFFICE

165,098

PNEUMATIC TIRE

Marcia G. Muszynski, Detroit, Mich., assignor to
United States Rubber Company, New York,
N. Y., a corporation of New Jersey

Application January 14, 1950, Serial No. 7,265

Term of patent 14 years

(Cl. D90—20)

To all whom it may concern:

Be it known that I, Marcia G. Muszynski, a citizen of the United States of America, residing in Detroit, county of Wayne, and State of Michigan, have invented a new, original, and ornamental Design for a Pneumatic Tire, of which the following is a specification, reference being had to the accompanying drawing, forming part thereof, wherein:

Fig. 1 is a side elevational view of a pneumatic tire showing my new design; and

Fig. 2 is a fragmentary perspective sectional view thereof taken on the line 2—2 of Fig. 1.

The dominant feature of the design resides in the combination in a sidewall of the tire, of a relatively narrow substantially white sidewall zone adjacent the tire bead, and an outwardly projecting circumferential rib surrounding said sidewall zone, said rib and the sidewall between said

rib and the tire tread being of a relatively dark color.

I claim:

The ornamental design for a pneumatic tire, as shown and described.
